UNITED STATES PATENT OFFICE.

ARTHUR J. RAY, OF CUBA, AND RUDOLPH F. STEHLIK, OF CHICAGO, ILLINOIS, AS-SIGNORS, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed February 2, 1925, Serial No. 6,181. Renewed July 5, 1928.

The present invention relates in general to telephone systems, but is concerned more particularly with telephone systems in which arrangements are provided for absorbing one or more digits in certain of the telephone numbers, and is concerned still more particularly with telephone systems in which the absorbing arrangement comprises a so-called "drop-back" selector—i. e., a selector which responds to a digit and then restores to its normal position after which it responds to the next digit dialled and selects an idle trunk in the desired level after the fashion of any ordinary selector.

One feature of the present invention is the provision of a new and improved circuit arrangement in a discriminating drop-back selector which is required to drop back from a majority of its levels, but not from the others. According to this feature, the selector is provided with circuit arrangements which normally cause the selector to drop back in response to any first digit, in conjunction with contacts operated in accordance with the extent of the first movement of the switch in response to such first digit to prevent the dropping back of the selector on a certain level, or certain levels, as the case may be.

There is another feature of this invention which consists in a new and improved circuit arrangement for preventing the automatic rotary movement from taking place on levels from which it is desired to drop back, and this arrangement consists in the provision of shaft-controlled contacts for opening the circuit of the rotary magnet when the shaft is raised to a level from which the drop back is to be made, in conjunction with contacts on the release magnet for maintaining the circuit of the rotary magnet open until the shaft reaches its normal position.

Another feature of this case relates to the provision of a new and improved arrangement for insuring that the relay which operates in series with the release magnet when the normal position is reached by the shaft of the selector after it has dropped back to absorb a digit does not pull up and open its

initial circuit before the core of the relay winding has become magnetized throughout its length, as will be hereinafter explained.

According to another feature of the invention, circuit arrangements are provided for busying the drop-back selector during its releasing operation so as to prevent false operation which would otherwise occur if the switch were permitted to be seized before it is fully released.

Another feature of this case which may be considered as more or less dependent upon the preceding one, is concerned with the provision of circuit arrangements whereby the switching relay of the switch is disconnected from the release trunk conductor during the releasing operation to prevent its energization which would otherwise occur responsive to the grounding of the release trunk conductor.

Referring now to the accompanying drawings, Fig. 1 shows a trunking layout illustrating one situation in which the new and improved drop-back selector may be used to an advantage, and Fig. 2 is a circuit drawing of a drop-back selector embodying the features of the invention.

Referring now particularly to Fig. 1, this drawing shows the selector D which is located in an office of a multi-office network embracing not more than ten automatic offices of an ultimate capacity of 10,000 lines each. It is assumed, however, that at present only the #4 office has more than one thousand lines assigned and that the other offices are accordingly of one thousand lines capacity or less. That being the case, thousands selectors are required in the #4 office but not in the other offices.

Trunks leading to thousands selectors in the #4 office terminate in the fourth level of the selector D. One of these thousands selectors is the selector E. The hundreds selector F' and the connector H' may be used to extend a connection to the line of substation A².

Trunks leading from the sixth level of the selector D extend to hundreds selectors in the sixth office which, at present, has a capacity of not more than 1000 lines. One of these

trunk lines terminates in the selector F which may be used in conjunction with the connector H to extend the connection to the line of substation A'.

5 The remaining working levels of the selector D are understood to be connected up in a manner similar to the sixth level.

Regarding the selector D itself, it may be pointed out that this is a standard two-wire selector of the usual vertical and rotary type with certain extra equipment consisting of an added relay 21 and the shaft springs which operate on the fourth level, together with certain other circuit arrangements, all of which 15 co-operate together to bring about the desired action of the selector which is to release on the calling of any digit unless it is prevented from doing so by the operation of the shaft springs, and to act like any ordinary selector 20 upon the dialling of the next digit in case it releases in response to the dialling of the digit in question.

The invention having been described generally, a detailed description of the operation of 25 the apparatus shown will now be given. For this purpose, it will be assumed that the subscriber at substation A desires to converse with the subscriber at substation A', whose number is 66461. The subscriber at substation A now removes his receiver, whereupon the individual line switch extends the calling line to the terminals (such as 2, 3, and 4) of an idle first selector switch, which selector, it will be assumed, is the selector D.

30 When the selector D is seized, as above pointed out, line relay 22 energizes over conductors 5 and 7 and over the calling line and closes at armature 31 a circuit for release relay 23. Release relay 23 energizes and prepares the switch for operation at armatures 33 and 34 and at armature 32 places ground on the release trunk conductor 6 so as to maintain the line switch C operated.

When the calling subscriber turns his calling device in accordance with the first digit in the desired number, in this case the digit "6", line relay 22 deenergizes momentarily for each of the six interruptions produced in its circuit by the calling device at the calling 45 substation. Each time it deenergizes, line relay 22 closes at armature 31 a circuit through armature 33 and its working contact and the series relay 24 for vertical magnet 47. By the operation of vertical magnet 47, the wipers 48-50 are raised step by step and they come to rest opposite the desired level of bank contacts, in this case the sixth level. Relay 50 55 is energized in series with vertical magnet 47 upon the first impulse of current being delivered to the latter and, being slow acting, maintains its armature attracted throughout the series of impulses. At armature 39, relay 24 disconnects the grounded release trunk conductor 6 from the off normal contacts 37, 60 so as to prevent the premature operation of

release magnet 36. At armature 40, relay 24 closes a point in the circuit of stepping relay 25 which is completed at off normal contacts 54 upon the first vertical movement of the shaft. This circuit starts from the 70 grounded release trunk conductor 6 and includes armature 38 of release magnet 36 and its resting contact, working contact and armature 40, and off normal contacts 54. Upon the completion of this circuit for relay 75 25, relay 25 energizes and closes at armature 41 a locking circuit for itself which includes the resting contact and armature 45 of switching relay 26, working contact and armature 41, and the interrupter contacts 55 80 of the rotary magnet 56, in addition to the off normal contacts 54. At armature 42, relay 25 closes a point in the circuit of rotary magnet 56.

Since the sixth level is the one called and 85 since the shaft springs are operated on the fourth level, these springs are momentarily operated as the operating portion of the shaft passes by the projection on the shaft spring nearer the shaft. This, however, does not produce any effect, as may be seen upon an examination of the circuit, because relay 24 is energized at this time.

At the end of the vertical movement on the switch, relay 24 falls back and closes at the normally closed contacts controlled by armature 40, a point in the circuit of rotary magnet 56. This circuit is not completed at this time, however, because the shaft contacts 9 are open. At armature 39 relay 24 closes a circuit from the grounded release trunk conductor 6, through off normal contacts 37, normally closed shaft contact 8, armature 27 of relay 21 and its resting contact, and off normal contacts 35 for release magnet 36. Responsive to the closure of this circuit, release magnet 36 pulls up and at armature 38 90 opens a still further point in the circuit of rotary magnet 56 so as to prevent a momentary closure of the rotary magnet circuit at contacts 9 as the shaft passes the fourth level. Armature 38 of the release magnet also connects the release trunk conductor 6 to the release magnet circuit at a point between contacts 9 and armature 27, thereby preventing a momentary opening of the release magnet circuit at contacts 8 as the switch shaft passes the fourth level on its 100 way to its normal position. As a further result of the energization of the release magnet, the shaft of the switch is restored to its normal position, whereupon off normal contacts 35 and 54 are opened. Contacts 54 open the circuit of relay 25 which accordingly falls 110 back and disconnects rotary magnet 56 at armature 42 and opens a further point in its previously closed locking circuit at armature 41.

Off normal contacts 35 open a point in the 130

- previously traced circuit of release magnet 36. The circuit of the release magnet 36 is not completely opened at this time on account of the fact that the lower winding of relay 5 21 is bridged around the off normal contacts 35 (through armature 34 and its working contact). Accordingly, the lower winding of relay 21 is energized in series with release magnet 36.
- 10 Upon the energization of relay 21, a locking circuit is closed at armature 28 for the upper winding of the relay. At armature 30, the shaft springs 9 are shunted so as to permit the switch to rotate on any one of its 15 levels upon its second operation. Armature 27 opens the release magnet circuit and also the circuit of the lower winding of relay 21, whereupon the release magnet falls back, but relay 21 remains locked up to conductor 6.
- 20 It will be seen that the net results of the dialling of the first digit is that the selector D has raised its wipers opposite the level (the sixth) corresponding to such digit and has 25 restored its shaft and wipers to their normal position, and that the relay 21 of the selector D has operated to prevent the absorbing action when the next digit is dialled.
- When the second digit "6" is dialled, the 30 shaft and wipers of the selector D are again raised to the sixth level in the manner described hereinbefore and relay 25 is again pulled up and locks itself at armature 41, in addition to preparing the rotary magnet circuit at armature 42.
- At the end of the vertical movement of the shaft, relay 24 falls back as before, but does not close a circuit for release magnet 36 at armature 39 at this time on account of the 40 fact that armature 27 is now operated by relay 21. At the normally closed contacts controlled by armature 40, a circuit is closed from the grounded release trunk conductor 6 through armature 38 and its resting contacts, 45 contacts controlled by armature 40, working contact and armature 30 of relay 21, and the working contact and armature 42 of the stepping relay 25 to rotary magnet 56. Rotary magnet 56 energizes upon the closure of this 50 circuit and advances the wipers 48-50, inclusive, into engagement with the first set of contacts in the sixth level. Near the end of its stroke, the rotary magnet opens the interrupter contacts 55, whereupon stepping relay 25 falls back and opens a point in its locking circuit at armature 41, and at armature 42 opens the circuit of the rotary magnet. The rotary magnet now falls back and closes its interrupter contacts 55 again.
- 60 From this point the operation depends upon whether the trunk terminating in the first set of bank contacts is busy or idle. If it is idle, a circuit is now completed from the grounded release trunk conductor through release magnet armature 38 and its resting contacts 65 to relay 26, resting contact and armature 41, and contacts 55 and 54 to battery through stepping relay 25. Accordingly, relay 26 energizes, seizing the trunk.
- Assuming on the other hand that the trunk line is busy, stepping relay 26 is short circuited by the ground potential encountered upon the busy test contact by test wiper 49 and does not energize. In this case, stepping relay 25 energizes through test wiper 49 and again completes its locking circuit at armature 41, at the same time closing the circuit of rotary magnet 56 at armature 42. The rotary magnet now energizes again and advances the wipers into engagement with the next set 70 of bank contacts.
- This alternate operation of relay 25 and magnet 56 continues as described until an idle trunk is reached, which trunk, it will be assumed, is the trunk comprising conductors 85 51-53. When this idle trunk is reached, relay 26, being no longer short circuited, energizes responsive to the closure of its circuit at interrupter contacts 55 upon the falling back of rotary magnet 56 subsequent to the 90 advance of the wipers to the idle trunk by the rotary magnet. Upon energizing, relay 26 removes ground from the working contact of armature 41 and from armature 31 at armature 45; it disconnects test wiper 49 from the junction of its own winding and that of stepping relay 25 at armature 44 and connects it instead to the grounded release trunk conductor 6, thereby making the seized trunk 95 busy; and at armatures 43 and 46, relay 26 disconnects the incoming line conductors 5 and 7 from the windings of line relay 22 and extends them by way of wipers 48 and 50 to the corresponding conductors 51 and 53, respectively, of the seized trunk line, which is 100 assumed to be the trunk line leading to the selector F, Fig. 1. When this occurs, the line and release relays (not shown) of the selector F are energized and the latter places ground 105 on the release trunk conductor 52, thereby 110 closing the usual holding circuit for the selector D before the slow acting release relay 23 has had time to fall back.
- It will be noted that the designation of the selector F is "66" and it will be remembered 115 that these two digits have been dialled in order to extend the connection to this selector.
- When the subscriber manipulates his calling device in accordance with the third digit 4, the selector F raises its wipers opposite the fourth level of bank contacts and rotates them in search of an idle trunk line in the fourth level. Assuming that the trunk line extending to the connector H is the one selected, this switch is now prepared for operation in the 120 usual manner.
- In response to the dialling of the next two digits 6 and 1, the connector H raises its wipers opposite the sixth level and brings them into engagement with the first set of 130

contacts (not shown) in that level, which are the contacts in which the line of substation A' terminates. The usual ringer at the called substation is now actuated over the called 5 line by the connector H in the usual manner.

When the called subscriber removes his receiver, the ringing current is removed and the talking connection is completed in the usual manner, whereupon the two subscribers 10 may converse with each other as desired.

When the conversation is terminated, the two subscribers replace their receivers with the result that the ground potential is removed from the release trunk conductor of 15 the established connection by the connector H and the ground is accordingly removed from release trunk conductor 52, Fig. 2. When this occurs, relays 21 and 26 of the selector D fall back. At armature 45, relay 20 26 closes a circuit through armature 31 and its resting contact, armature 33 and its resting contact, and off normal contacts 35 for release magnet 36, which thereupon energizes and restores the switch to its normal position. 25 The circuit of release magnet 36 is opened at off normal contacts 35 when the normal position is attained. It will be noted that the lower winding of relay 21 is disconnected from around the off normal contacts 35 at 30 armature 34 of release relay 23 at this time so as to prevent any interference with the releasing operation.

Considering now a call from the line of substation A to the line of substation A', 35 and assuming that, when the subscriber at substation A removes his receiver, the line switch C selects the selector D as hereinbefore described and that the selector D is accordingly prepared for operation in the same 40 manner as before. The dialling of the first digit "4" in the desired number results in the transmission of four impulses to vertical magnet 47 through series relay 24 with the result that the wipers 48-50 are raised opposite the fourth level of bank contacts. Since the office in which the line of substation A' terminates is a fully equipped ten thousand 45 line office, no digit is to be adsorbed at this time. Therefore, the shaft springs are operated by the switch shaft at this time to prevent the absorbing of the office digit. The contacts 8 open a point in the circuit through which release magnet 36 was previously operated to restore the switch to normal at the 50 end of the first digit, and the contacts 9 close a point in the circuit of the rotary magnet 56 so that the rotary magnet may operate as soon as the series relay 24 falls back at the end of the digit. For the sake of clarity it 55 may be well to mention that the circuit of rotary magnet 56 at this time is as follows: from ground by way of the grounded release trunk conductor 6, armature 38 and its resting contact, normally closed contacts controlled 60 by armature 40, the fourth level shaft con-

trolled contact 9, working contact and armature 42, and rotary magnet 56 to battery. The operation of the rotary magnet 56 and the subsequent operation of the selector is the same as described hereinbefore, and assuming 70 that the selector E is the one seized, this selector, together with a hundreds selector (for example, the selector F') and a connector (for example, the connector H') are operated to extend the connection to the line of 75 substation A' responsive to the dialling of the remaining four digits 4, 8, 9, and 0.

At the end of the ensuing conversation, the connection is released in the usual manner.

Regarding the arrangement for maintaining the release trunk conductor 6 grounded during the regular releasing operation of the selector, it will be remembered that, when ground is removed from the release trunk conductor of the trunk upon which the wipers 80 of the switch are standing, relay 26 falls back and closes at armature 45 a circuit through armatures 31 and 33 and off normal contacts 35 for release magnet 36. Also, relay 21 is unlocked and falls back in case it is operated 85 at this time. Release magnet 36, upon energizing responsive to the closure of its circuit, closes at armature 38 and its front contact a point in the circuit through which it is locked to the release trunk conductor during the 90 drop-back release of the switch. At this time, however, since the regular release circuit is closed, and since release trunk conductor 6 is not grounded otherwise, the effect is entirely 95 different; the release magnet is not locked up to the release trunk conductor 6, but instead the ground potential which is being supplied to the release magnet through armatures 31 and 33 is extended through the resting contact and armature 27 of relay 21 100 to the working contact and armature 38 to release trunk conductor 6 to maintain the selector D busy during its releasing operation. It will be noted that armature 38 disconnects the lower terminal of the switching 105 relay 26 from the release trunk conductor 6 at its resting contact so as to prevent an energization of relay 26.

When the switch reaches its normal position, off normal contacts 35 open the circuit of release magnet 36, whereupon release magnet 36 falls back and disconnects release trunk conductor 6 from ground and connects it to relay 26 again.

It will be appreciated that if it were not for 115 the provision of the above explained arrangement for preventing a possible seizure of the selector D during its releasing operation, such a seizure might well occur with the result that relays 22 and 23 might be energized by 120 the time the normal position of the switch is reached, in which case relay 21 operates prematurely (and locks up) because its lower winding is placed in multiple with off normal contacts 35 by armature 34 of relay 23. The 125 130

likelihood of this occurrence, however, is obviated in the manner above pointed out.

Regarding the utility of the resistance element 29, it may be pointed out that, in many cases, double wound relays are available which have their low resistance windings placed upon the armature end of the cores and their locking windings upon the heel end of the cores. A relay of this type is usually wound so that the low resistance winding has sufficient turns to produce a comparatively heavy pull when the winding is inserted into the circuit in series with the release magnet. It has been found by experiment that the flux generated by this low resistance winding is sufficient to attract the armature of the relay so quickly that the relay operates to close its locking circuit and to open the circuit of its energizing winding with the portion of the core encircled by the locking winding practically unmagnetized and with the armature being attracted only by the leakage flux which takes a path excluding the heel end of the core. Under such conditions, the magnetism in the armature end of the core dies away responsive to breaking of the circuit of the low resistance winding and permits the armature of the relay to be retracted before the flux can be built up through the heel end of the core sufficiently to exert a holding influence upon the armature. As a result, the locking circuit is again opened and the initial circuit is again closed and the relay merely buzzes instead of operating fully and locking up as desired.

In order to prevent the above occurrence, the low resistance winding of the relay may be made (in relays constructed especially for operation in this circuit) of a smaller number of turns of wire, so that the flux generated by this winding when it is connected in series with the release magnet of the switch is not sufficient to operate the armature of the relay until it has permeated the entire core and heel piece. When the circuit of the locking winding is closed under these conditions, the flux is already built up, and it is only necessary for the locking winding to maintain the established flux in order to hold the armature in its operated position.

In order to adapt relays for use in this circuit which have not been wound especially for this specific circuit, it is deemed best to shunt the low resistance winding with the low resistance element 29 which cuts down the current flow through the winding to such an extent that the relay operates in the desired manner.

It is appreciated that the resistance 29 might be made higher and in that case be placed in series with the lower winding of the relay 21, but, in this case, the release magnet 36 would probably not remain energized in series with the high resistance necessary to 65 cut down the current flow sufficiently to adapt

the lower winding of the relay to operate as desired, and there would be a likelihood that the release magnet might fall back and open the circuit of the lower winding of the relay before a sufficient time is allowed for the relay to operate and become locked up.

What is claimed is:

1. In an automatic switch of the drop-back type, circuit arrangements whereby the switch normally restores to its normal position to absorb a digit, except when a certain digit is called, and contacts controlled in accordance with the extent of the movement of the switch when the same is operated in accordance with such certain digit to prevent such restoration of the switch to normal.

2. In a drop-back switch, circuit arrangements including contacts at which the rotary magnet circuit is open and contacts at which the release magnet circuit is closed at the end of the primary movement of the selector, said contacts in the rotary magnet circuit being closed during the release of the switch, and contacts on the release magnet for maintaining the rotary magnet circuit open until the normal position of the switch is attained.

3. In a telephone system, a selector switch having a release magnet, a release trunk conductor, and a switching relay normally connected to such conductor, a circuit for applying ground to said conductor during the releasing operation of the selector, and contacts on said release magnet for disconnecting the switching relay from the said release trunk conductor.

4. In a drop-back switch of the type in which a relay has its winding shunted around off normal contacts to effect the energization of the relay when the off normal contacts open responsive to the dropping back of the switch from a critical level, a locking winding on the same relay, contacts for closing a circuit through the locking winding to maintain the relay operated independent of the first named winding, other contacts for opening the circuit of the first named winding, and a resistance element shunted around the first named winding so as to adapt the relay for operation as above set forth.

5. In an automatic switch having wipers, means including a rotary magnet for moving the wipers from their normal position, a release magnet for restoring the wipers to their normal position, a guarding conductor for said switch, and contacts on said release magnet for applying a guarding potential to said guarding conductor and for opening the circuit of said rotary magnet during the releasing operation.

6. In a telephone system, a selector switch and means for operating the same, said switch having a primary movement and an automatic selecting secondary movement, a slow acting relay energized during the initial primary movement and deenergized on the

completion thereof to automatically release the switch after the initial primary movement, and shaft controlled springs operative in case the switch is operated to a predetermined point on its initial primary movement for preventing the automatic release of said switch and for starting the automatic selecting secondary movement.

7. In a telephone system, a selector switch and means for operating the same, said switch having a primary movement and an automatic secondary movement, a release magnet for said switch, circuit arrangements whereby a circuit for said release magnet is normally closed after an initial primary movement of said switch to automatically release the same, a relay for preventing the automatic release of said switch on a subsequent primary movement, contacts on said release magnet and contacts on said relay, an energizing circuit for said release magnet including said relay contacts, a locking circuit for said release magnet including said relay contacts and said contacts on said release magnet, and an energizing circuit for said relay including the windings of said release magnet and relay in series.

8. In a digit absorbing or drop back selector having primary and secondary movements, a release magnet, a change-over relay energized during the primary movement and deenergized on the completion thereof, a circuit for said magnet normally closed by the deenergization of said relay to cause said magnet to energize and automatically release the switch, a second relay, contacts on said release magnet closed when said magnet is energized for closing a circuit to operate said second relay, and contacts controlled by said second relay for altering the switch circuits so that a subsequent primary movement will be followed automatically by the secondary movement upon the subsequent deenergization of said change-over relay.

9. In a telephone system, a selector switch for use in connecting calling and called lines, groups of trunk lines, said switch having directive primary movement to select a group and automatic secondary movement, to select an idle trunk line in the selected group, a stepping relay for controlling the automatic secondary movement, a switching relay for electrically connecting said switch with said selected trunk, a circuit for said stepping relay controlled by said switching relay including contacts on said switching relay, an energizing circuit for said switching relay including the winding and a contact of said stepping relay, the circuit of said switching relay adapted to be opened at said contact when the stepping relay is energized, and a shunting circuit for said switching relay including the said contact in said stepping relay.

10. In a telephone system, a selector switch

and means for operating the same, said switch having a primary movement and an automatic secondary movement, a release magnet for said switch, a change-over relay energized during the primary movement and deenergized on the completion thereof, contacts on said relay closed on its deenergization for energizing said release magnet to automatically release the switch, a guarding conductor in said switch, contacts on said magnet for closing a locking circuit for itself which is effective until the switch is restored, means whereby the switch may be reoperated to set up a connection and can be released thereafter, and a circuit including the said contacts on said magnet for placing a guarding potential on said guarding conductor during the last mentioned releasing operation.

11. In a telephone system, a selector switch having primary and secondary movements, means including a rotary stepping circuit for operating said switch to establish a connection, a guarding conductor for said switch, a release magnet for said switch, means for placing a guarding potential on said guarding conductor, means in said switch responsive to the removal of guarding potential from said conductor for operating said release magnet to release said switch, and contacts on said release magnet for replacing guarding potential on said guarding conductor and for disabling said rotary stepping circuit during the release of said switch.

12. In a telephone system, a selector switch, means for operating said switch to establish a connection, a release magnet operated to release said switch once during the establishment of said connection and once thereafter, a guarding conductor in said switch, contacts on said release magnet for closing a locking circuit for itself upon its first operation, means for opening said locking circuit, and means for placing a guarding potential on said guarding conductor during the last operation of said release magnet, said last means including said contacts.

13. In a telephone system, a selector switch, means for operating said switch, a guarding conductor in said switch, a release magnet in said switch, means for operating said release magnet under different conditions to release said switch, and contacts on said release magnet for closing a locking circuit for itself when the magnet is energized under one condition and for placing a guarding potential on the guarding conductor during the release of said switch when the magnet is energized under another condition.

14. In an automatic switch of the drop-back type having primary and secondary movements, circuits normally closed after the primary movement to cause said switch to restore to normal position to absorb a digit, and contacts controlled in accordance with the ex-

tent of the primary movement of the switch to prevent the restoration of said switch to normal.

15. In an automatic switch of the drop-back type having primary and secondary movements, means normally effective to automatically release said switch responsive to the completion of its primary movement, and means for preventing the release of said

switch responsive to a particularly primary movement.

In witness whereof, I hereunto subscribe my name this 29th day of January, A. D. 1925.

ARTHUR J. RAY.

In witness whereof, I hereunto subscribe my name this 29th day of January, A. D. 1925.

RUDOLPH F. STEHLIK.
